UNITED STATES PATENT OFFICE.

WILLIAM E. YOULE, OF LOS ANGELES, CALIFORNIA.

UNDERREAMER.

Application filed August 9, 1921. Serial No. 491,017.

To all whom it may concern:

Be it known that I, WILLIAM E. YOULE, a citizen of the United States, residing at Los Angeles, in the county of Los Angeles and State of California, have invented a new and useful Underreamer, of which the following is a specification.

This invention relates to underreamers of the impact type particularly adapted for use with the cable system of well drilling, the main objects of the invention being to provide an underreamer which is far superior to any in the prior art, by reason of its great strength, especially in the shanks 15 of the cutters, the ease with which the cutters can be removed from the body without disconnecting the cutter operating spring, and especially by reason of certain provisions and features of construction by which 20 the spring bolt if broken will still be retained against loss and enabling the cutters to be retained within the body even though the spring bolt be broken.

Another object of major importance resides in the expanding operation of the cutters which are translated from collapsed to expanded positions in stepped movements first unlatching and expanding the cutters to a point slightly less than full expanded 30 position, translating the cutters vertically upward and subsequently completing the expanding movement, whereby a slight collapsing relief of the cutters is provided to release the cutters, when wedged in a well bore, without effecting a latching of the cutters.

Another object is to provide an underreamer in which the supporting engagement 40 of the cutters upon the spring bolt is below the shanks of the cutters, whereby the shanks are devoid of weakening apertures or recesses.

A further object resides in the provision 45 of a one-piece body having a side opening spring chamber with a spring retaining nut on the spring rod, which is retained against turning by engagement with the walls of the recess whereby the tension of the spring can be regulated by a turning of the spring 50 rod.

Another object is to provide an underreamer in which the spring rod has a supporting engagement with the body portion 55 of the cutters whereby I am permitted to provide solid imperforate cutter shanks and in which the cutters have inthrust bear-

ing projections which overlap each other when the cutters are in collapsed position, this overlapping structure permitting the cutters to be constructed so that they will 60 come closely together when collapsed, so that they can be expanded to a maximum degree and when expanded will leave a maximum open space therebetween to receive the drilling refuse, and so as to have a great 65 width of cutter shank in the direction of cutter expansion.

Another object is to provide an underreamer from which the cutters may be removed without disturbing the spring and 70 spring rod.

Other objects reside in the provision of maximum upthrust bearing surfaces, outthrust bearing surfaces, and inthrust bearing surfaces on the body and on the cooperating cutters, the provision of means preventing the cutters dropping from the body when the supporting spring bolt breaks, and in the provision of means whereby a 75 broken spring rod is retained by the cutters 80 against dropping from the body.

Various other objects and advantages will be more fully apparent from the following description of the accompanying drawings which form a part of this disclosure, and 85 which illustrate a preferred embodiment of the invention.

Of the drawings

Figure 1 is a side elevation of my improved underreamer, with the cutters in expanded position.

Fig. 2 is a similar elevation of the lower portion of the underreamer, with the cutters in collapsed position.

Fig. 3 is an enlarged plan section on line 95 x^3-x^3 of Fig. 1.

Fig. 4 is a plan section on line x^4-x^4 of Fig. 5.

Fig. 5 is a vertical section showing the cutters in closed position.

Fig. 6 is a plan section on line x^6-x^6 of Fig. 5.

Fig. 7 is a section similar to Fig. 5, showing the cutters in relief position and prior to their final movement of expansion.

Fig. 8 is a plan section on line x^8-x^8 of Fig. 7.

Fig. 9 is a section similar to Fig. 7, showing the cutters in fully expanded position.

Fig. 10 is a detail vertical section through 110 the lower portion of the reamer body.

Fig. 11 is a side elevation partly in sec-

tion, of the reamer body, looking from the right side of Fig. 10.

Fig. 12 is a bottom plan view partly in section, of Fig. 9.

5 Fig. 13 is a vertical section illustrating the method of removing the cutters from the body.

Fig. 14 is a detail bottom plan view of the reamer body.

10 Fig. 15 is a perspective view of the lower portion of the reamer body.

Fig. 16 is an elevation of the lower portion of the underreamer looking from the right side of Fig. 1.

15 Fig. 17 is a detail perspective view of the lower end of the spring bolt.

Figs. 18 and 19 are detail perspective views of the cutters.

20 Fig. 20 is a diagram of the cutter movements of the ordinary types of underreamer, and

Fig. 21 is a similar diagram of the cutter movements of the underreamer of the present invention.

25 When reaming in soft sticky formation with reamers of the general type herein referred to and also when reaming in hard rock the cutters sometimes become stuck in the well bore; with the ordinary forms of underreamers now in use the cutters are released from such stuck or wedged condition by elevating the reamer body until the cutters are fully collapsed and latched beneath their expanding shoulders.

30 In some formations the cutters stick at every stroke and the repeated latching under the heavy snapping tension of the spring causes crystallization and breaking of the working parts.

40 In the underreamers of the present invention by a relatively short movement of the body relative to the cutters, the cutters are permitted a slight primary collapsing movement independent of the main latching, to release the stuck or wedged cutters, and this primary movement is gradual relative to the abrupt latching movement which is effected by a substantially greater movement of the body relative to the cutters.

45 Further in the usual types of underreamers in which the cutters are supported by a spring rod, the rod's head usually engages into recesses or slots in the cutter shanks and in such cases the recesses or

50 slots so weaken the shanks that under severe usage they break off and the cutters drop from the reamer body. In my improved tool the head of the spring rod engages into pockets in the main body portion of the cutters, and the rod and said pockets are so

55 formed that if the rod becomes broken it will be retained in the tool. This structure permits me to form the cutter shanks without any weakening slots or recesses and of

great size and strength compared with those now in general use.

60 By providing a means independent of the spring rod, for retaining the cutters against dropping from the body I effectively prevent a loss of one or both cutters even though 70 the spring rod should become broken and lost in the well hole.

65 Referring now to the drawings a detailed description of the preferred form illustrated will be given with like parts throughout the 75 several views correspondingly numbered.

The underreamer body.

With particular reference to Figures 1, 10, 11, 14, 15, and 16 I will first describe the 80 formation of the body 1 of the underreamer which is of cylindrical form with its upper portion provided with a squared shank 2 and a tapered threaded pin 3 adapting it to be joined to other elements of a tool string. 85 The medial portion of the body has a side opening recess providing a spring chamber 4 and the lower portion of the body has diametrically opposed slots 5—5 extending upwardly from the lower surface of the 90 body and inwardly to a central web 6 providing inthrust bearing surfaces 7—7 for engagement by the shanks of the cutters, the opposed side walls of each slot being 95 grooved to provide slideways 7^a for the cutters and define outthrust bearing surfaces 8. The web 6 extends upwardly to approximately the same height as the slots 5 and above said web the slots merge together 100 to form a chamber 9 of a width coinciding with the base of the grooves in the side walls of the slots. The web 6 terminates short of the lower end of the body, with its lower surface inclined from the center 105 of the body outwardly and upwardly to provide cutter latching and expanding shoulders 10—10 and the body is provided with V-shaped projections 11—11 extending downwardly on opposite sides of the slots 5—5, said projections defining the inner 110 limits of the upthrust bearing surfaces 12—12 of the body and providing opposed inthrust supporting or bearing surfaces 13—13. These faces are the preferred 115 means for rigidly resisting or supporting the inthrust of the cutters when they are in operation.

The opposite walls of the chamber 9 have rectangular orifices or slots 14 transversely aligned with their outer faces or walls flush with the wall of the chamber and their lower walls approximately aligned with the top walls of the slots 5. (See Figs. 10, 11, 15.) Circularly spaced from one of the slots 14 I provide recesses 15—16 with the intermediate walls having a transverse bore 17 aligned in a plane intersecting the center of the orifice. The openings 14 are adapted to re-

ceive a removable retaining key 18 which extends across the chamber 9 and is retained in place by a split cotter pin 19 inserted through the bore 17 and through a hole in 5 said key with the ends of the pin spread apart to retain it in place. (See Figs. 4 and 16). The function of this retaining key will be fully explained later.

It will be evident that to properly machine the chamber 9 would be difficult if not impossible, therefore, it will be stated that my preferable method of forming the chamber consists of cutting directly through the body the full height and width of said 10 chamber and after the body is properly machined the walls 20 are formed of separate pieces of the contour indicated by heavy dotted lines in Fig. 11, and subsequently welded or brazed in place.

20 I provide spring actuated means for pulling the cutters upwardly in the body. For this purpose the walls separating the chamber 9 and the spring chamber 4, and the web 6 of the body have centrally disposed vertically alined bores 21-22 to accommodate a spring rod 23 having an approximately square head 24 at its lower end. (See Fig. 17). Said head is positioned below the web 6 of the body with the rod extending upwardly into the spring chamber 4 and the upper end of the rod is screw-threaded into a square nut 25. An actuating spring 26 surrounds the rod between the lower wall of the spring chamber and the nut 25; the spring chamber is preferably of slot form adjacent the nut so that the sides of the nut will engage the side walls of the spring chamber to prevent a turning of the nut; hence by a rotation of the spring rod 23 the tension of the spring 26 can be varied as desired (see Figs. 3 and 16). The head 24 provides opposed cutter supporting table surfaces 27 and the head is strengthened by fillets 28. (See Fig. 17).

45 *The cutters.*

The cutters and the body are provided with means whereby a relative upward and downward movement of the body collapses 50 and expands the cutters. The cutters are of duplicate construction, (see particularly Figs. 18 and 19), each having a body portion 30 and a shank 31, the upper surface of the cutter body having upthrust bearing surfaces 32, 32 on opposite sides of the shank. Projecting from the upper portion 55 of the inner surface of the cutter body I provide angle shaped projections 33, 33 providing inthrust bearing surfaces 34, 34, and adjacent angle shaped recesses 35, 35, one projection and one recess being on one side of the center of the cutter body and one projection and one recess being on the opposite side with each pair reversely arranged 60 so that when the two cutters come together

in collapsed position the opposed projections 33 and recesses 35 will intermesh. A pocket 36 is formed in the inner surface of the cutter body 30 to receive the head 24 of the spring rod 23, said pocket defining 70 ledges 37, 37 adapted to rest upon the supporting table surfaces 27, 27 of the bolt head 24, and a lower wall or face 38 which serves as a means for preventing the bolt dropping from the tool. The lower portion 75 of the inner face of the cutter shank 31 has a boss with an inclined upper end operating as a cutter expanding cam 40, and with adjacent guide surfaces 41-41, the boss and the cutter body being centrally grooved to 80 provide clearance for the spring rod 23 and head fillets 28.

The cutter shank 31 has the usual cam shoulder 42 on its outer side and the opposite sides of the shank have projecting guide 85 ribs 43 for guiding the shank in the slide-ways 7^a of the tool body 1. Said ribs define cutter outthrust bearing surfaces 44 and are cut away as at 44^a to facilitate removal of the cutter from the tool body as will later 90 be described.

The upper ends of the cutter shanks are transversely grooved on opposite sides as at 45, the height or length of each groove being slightly greater than the full vertical 95 movements of the cutters plus the height of the cutter retaining key 18 previously described. The upper ends of the grooves 45 define elevated stop shoulders 46 and when the cutters are assembled in the tool 100 body the retaining key 18 which passes through one of the grooves 45 of each cutter with the stop shoulders 46 above the key so in case the cutter supporting spring rod becomes broken the cutters will be retained 105 in the tool by the key 18. While only one of the grooves 45 of each cutter shank engages over the key 18, the shank is provided with such a groove on each side of the shank 110 so as to provide a universal type of cutter instead of separate right and left hand cutters. The upper ends of the cutter shanks taper upwardly to allow for the various 115 rocking movements of the cutters during their expanding and collapsing operations and also during their insertion into and removal from the tool body.

A screw threaded hole is provided in the head of the spring rod to receive an eye bolt 47 (see Fig. 13) which is utilized during the 120 insertion or removal of the cutters.

Assembling and disassembling of cutters.

Assuming that the spring and spring rod is properly assembled in the body and that the rod is drawn down by suitable means attached to the eye bolt 47 (see Fig. 13), each cutter will be inserted into the body in the position of the left hand cutter in said figure, this being permitted by the clearance 125 130

provided by the cutaway portions 44^a of the ribs 43. As the pocket 36 of the cutter is now opposite the head 24 of the spring rod the cutter may be swung inward (as is the right-hand cutter in Fig. 13) the ledges 37 engaging over the companion table surfaces 27 of the bolt head 24 so that when the bolt is released it will elevate the cutters into the body with the ribs 43 of the cutters 5 slidably engaging into the slideways 7^a of the body. With the cutters so assembled the retaining key 18 is inserted through the body orifices 14 and secured in place by the cotter pin 19 as previously explained. A 10 removal of the cutters is effected by a reversal of the above operation.

Operation.

In collapsed condition the cutters assume 20 the position shown in Fig. 5 with the surfaces 50 of the cutters engaging the well casing as the underreamer is lowered into the well, to maintain the cutters collapsed. The cam shoulders 40 are engaged under the 25 expanding shoulders 10 of the web 6 of the body and the projections 33 and recesses 35 of the cutters are intermeshed on opposite sides of the head of the spring rod.

30 When the underreamer has passed through the casing shoe the cutters are free to be expanded and the spring 26 functions in the usual manner to draw the spring rod 23 upward to elevate and expand the 35 cutters.

During the first portion of the upward movement of the cutters the cutter expanding cams 40 slide outwardly from beneath the expanding shoulders 10 on the web 6 of the body and the cutters are thereby expanded to a point slightly less than full 40 expanded position. The cutters are then drawn vertically upward with the guide surfaces 41 contacting the bearing surfaces 7 of the web 6, to the position shown in 45 Fig. 7.

At the end of this vertical movement of the cutters their inclined inthrust bearing surfaces 34 are brought into contact with 50 the inthrust bearing surfaces 13 of the V-shaped projections 11 of the body and during the final part of the upward travel of the cutters the cooperation of these inthrust bearing surfaces expand the cutters 55 to their maximum degree, as shown in Figs. 1 and 9. It will, therefore, be understood that the cutters are first unlatched by the co-acting of the latch shoulders 10 and the cam shoulders 40 and expanded nearly to 60 their maximum degree, second, the cutters are drawn vertically upward with their guide surfaces 41 contacting the surface 7 of the body, and finally by the coacting of the inthrust bearing surfaces 13 and 34 of the body and cutters, the cutters are given

their final degree of expansion in which the latch shoulders 10 and cam shoulders 40 above referred to have no cooperation.

In collapsing the cutters they follow a reversal of the above described stepped movements from expanded to latched positions, the collapsing being accomplished in the usual manner by an engagement of the shoulders 42 with the mouth of the casing shoe which cams the cutters inwardly to latched position while the body 1 is being elevated.

With the cutters in expanded position, and having become stuck or wedged tightly in the well bore, it becomes necessary 80 to at least partially collapse the cutters to provide sufficient relief to free the cutters. With the ordinary types of underreamers this is accomplished by pulling the reamer body upward against the shoe 85 until a full latching of the cutters is effected, but in the present tool, I provide for a slight primary collapsing movement independent of the main latching, this primary collapsing of the cutters being initiated or accomplished by the upward movement of the body and its inclined inthrust bearing surfaces 13 along the cooperating inthrust bearing surfaces 34 of the cutters from the position illustrated in Fig. 9 to 90 that illustrated in Fig. 7. This provides collapsing relief to the degree indicated at 51 which is sufficient to release the stuck or wedged cutters. By effecting this collapsing relief without completely collapsing 95 and latching the cutters I eliminate to a great degree, the crystallizing effect which a repeated latching under the full tension of the spring produces and for this reason overcome the usual tendency of the moving parts to break under hard usage.

In Figs. 20-21 I have illustrated in diagram, the differences between the collapsing and expanding movements of the cutters of the ordinary types of underreamers and the underreamer of the present invention. In Fig. 20 is indicated the movements of the ordinary types of underreamers in which the full expanding of the cutters is performed in one movement *v* and in which *w* indicates the subsequent vertical movement of the cutter. In Fig. 21 is indicated the movements of the cutters of the underreamer herein, in which *x* indicates the unlatching and latching movement to effect the major portion of the expanding or collapsing of the cutters, *y* indicating the straight vertical travel of the cutters, and *z* indicating the final expanding and the primary collapsing movements. The movement in Fig. 20 is a two-step movement with the entire expanding and collapsing confined to one of the movements, while the movement in Fig. 21 is a three-step movement with the expanding and collapsing 110 115 120 125 130

divided and at opposite ends of the intermediate vertical movement.

From an examination of these diagrams it will be evident that in the ordinary type 5 of tool, the only collapsing relief available to release stuck or wedged cutters is by a full collapsing and latching of the cutters, while in the tool as herein shown and described a collapsing relief is immediately available independent of the main 10 collapsing and latching of the cutters.

As previously stated, in the event that the spring rod becomes broken it will be retained against loss and also that the 15 cutters themselves will be retained within the tool body. By reference to Fig. 9 it will be noted that with the cutters fully expanded, the space between the outer edges of the lower walls 38 of the pockets 36 in 20 the cutter bodies is less than the width of the head 24 of the spring rod 23, therefore it will be evident that it would be impossible for the rod to drop free from the cutters and as the rod constitutes the supporting means 25 for the cutters it will be plain that should the rod become broken both the cutters and the rod would drop together. Such dropping of the cutters will only continue until the stop shoulders 46 on the upper ends of the 30 cutter shanks strike the top of the retaining key 18 and as such key is rigidly fixed in the tool body it will be understood that the cutters cannot become lost from the body unless the heavy key 18 is broken or the 35 stop shoulders 46 of the cutter shanks become sheared off. One of the advantages of my device is that the key 18 limits the relative upward movement of the body 1, thereby preventing compression of the 40 spring sufficiently to break it.

It will become evident from the above detailed description that my improved underreamer fulfills each and all of the objects primarily stated and while the 45 specific structure illustrated is of a preferred embodiment it is to be understood that such modification and changes as fall within the language of the following claims are embraced in the broad scope of the invention.

I claim:

1. An underreamer comprising a body having slideways, cutters slidable therein, and means for translating the cutters, the 55 body and cutters having cooperating surfaces causing an expansion and maintenance of the cutters during their translation, in an intermediate expanded relation, and thereafter in a completely expanded relation.

2. An underreamer comprising a body having slideways, cutters slidable therein, and means for translating the cutters, the body and cutters having cooperating surfaces causing an expansion and maintenance 60

of the cutters in an intermediate expanded relation during the first portion of their translation and having other cooperating surfaces causing a final expansion of the cutters during the final portion of their 70 translation.

3. An underreamer comprising a body having slideways, cutters having shanks 75 slideable within said slideways, a spring actuated rod engaging the cutters below their shanks, and means on the body and independent of the rod for limiting the upward and downward movement of the cutters.

4. An underreamer comprising a body 80 having slideways, cutters having shanks slideable within said slideways and provided with pockets in their body portions below their shanks defining supporting ledges, and a spring actuated rod carried by the body 85 and having a head positioned within said pockets and having cutter supporting table surfaces engaging the supporting ledges of the cutters.

5. An underreamer comprising a body 90 having slideways, cutters having shanks provided with ribs slideable within said slide- 95 ways, and a spring actuated rod supporting and translating the cutters, the ribs having clearance notches permitting a removal of the cutters from the body without removing or disconnecting the spring actuated rod.

6. An underreamer comprising a body having slideways, a spring actuated cutter operating rod carried by the body, cutters 100 slideable in the slideways and engaging the rod, means removably carried by the body, operating when removed to permit removal of the cutters from the body while the rod is in operative condition.

7. An underreamer comprising a body having opposed slots defining an intermediate web having cutter expanding shoulders and with their side walls grooved to provide slideways, the body having angled inthrust bearing surfaces, cutters having shanks slideable in the slots, opposed ribs slideable in the slideways, cam shoulders normally latching under the expanding shoulders, and angled inthrust bearing surfaces; the combination 110 with the above named elements, of a spring actuated rod engaging the cutters and functioning to translate the cutters to cause an unlatching and expansion of the cutters by cooperation of the expanding shoulders of the body and the cam shoulders of the cutters, a subsequent vertical translation of the cutters without further expansion, and a final expansion of the cutters by cooperation 115 of the inthrust bearing surfaces of the body and the cutters.

8. An underreamer comprising a body having opposed slideways and intermediate projections providing inthrust bearing surfaces, opposed cutters having shanks slid- 120 125

able in said slideways, and a spring actuated cutter translating rod carried by the body and engaging the cutters, the inner opposed surfaces of the cutter bodies having angled 5 projections providing inthrust bearing surfaces and adjacent recesses on opposite sides of the rod, the projections of each cutter aligning to intermesh within the recesses of the opposite cutter.

10. An underreamer comprising a body having slideways, cutters slidable therein and having shanks with stop shoulders, means for translating the cutters in combination with means removably carried by the 15 body cooperating with said shoulders to limit the downward movement of the cutters.

10. An underreamer comprising a body having slideways, cutters having shanks 20 slidable therein and provided with stop shoulders adjacent their upper ends, means for translating the cutters, in combination with a transverse key located to one side of the translating means, carried by the body, cooperating with said shoulders to limit the 25 downward movement of the cutters and removable to permit a withdrawal of the cutters from the body.

11. An underreamer comprising a body having a spring chamber and a central bore 30 extending downwardly therefrom, a rod slidable within said bore and extending into the spring chamber, cutters supported upon the rod, a spring within said chamber surrounding the rod, and a nut screw threaded 35 on the upper end of the rod with its side faces engaging the sides of said chamber to maintain the nut against rotation, and slid- 40 able within the spring chamber to permit a regulation of the tension of the spring by a rotation of the rod.

12. In an underreamer, the combination 45 of a body having slideways, cutters slidable therein and having stop shoulders, means for translating the cutters located centrally in said body, means removably carried by the body located to one side of said translating means, and cooperating with said stop shoulders to maintain the cutters within the body if a disabling of said translating means occurs.

13. An underreamer comprising a body 50 having slideways, cutters slidable therein and transversely expandable, a spring actuated rod for operating the cutters having a fixed head with cutter supporting table surfaces on opposite sides of the rod shank extending across the shank in the direction of cutter expansion, and a nut mounted in the body and receiving the upper end of said spring rod to facilitate adjustment of the same.

14. An underreamer body having opposed 55 slots upwardly from its lower end defining an intermediate web providing cutter latching and expanding shoulders for initially

expanding the cutters, and projections extending from the lower end of the body on opposite sides of the slots and providing in-thrust bearing surfaces for completing the expanding of the cutters.

70

15. An underreamer body having opposed slots upwardly from its lower edge defining an intermediate web and a chamber above said web, the walls of said chamber being apertured to receive a cutter retaining key.

75

16. An underreamer body having opposed slots upwardly from its lower edge defining an intermediate web providing cutter latching and expanding shoulders, the side walls of the slots being grooved to form cutter 80 slideways having outthrust bearing surfaces, projections extending downwardly from the lower end of the body between the slots defining upthrust bearing surfaces on opposite sides of each projection and providing angled inthrust bearing surfaces.

85

17. An underreamer cutter having a shank defining an upthrust bearing surface on each side of the shank, ribs on the sides of the shank defining outthrust bearing surfaces, 90 and a transverse groove in the upper portion of the shank defining a stop shoulder.

18. An underreamer cutter having a shank defining an upthrust bearing surface on each side of the shank and ribs on the sides of the 95 shank defining outthrust bearing surfaces, a projection on the inner wall of the shank providing an expanding cam shoulder, and projections and adjacent recesses on the inner wall of the cutter body on opposite sides 100 of the shank adapted to intermesh with those of a companion cutter.

19. An underreamer cutter having a body portion and a shank defining upthrust bearing surfaces on the body on opposite sides 105 of the shank, ribs on opposite sides of the shank defining outthrust bearing surfaces, a projection on the inner wall of the shank defining an expanding cam shoulder, a 110 pocket in the inner wall of the cutter body defining cutter supporting ledges, and projections and adjacent recesses on each side of said pocket adapted to intermesh with those of a companion cutter with the projections forming angled inthrust bearing 115 surfaces.

20. In an underreamer, the combination of a body, a pair of expansible cutters mounted on the body, spring actuated means cooperating with the cutters and supported in 120 the body, said body permitting a longitudinal movement of the cutters on the body, and having faces receiving the inthrust of the cutters when the same are in their completely 125 expanded position, and operating by an upward movement of said body when the cutters are stuck in the hole, to withdraw said supporting faces and permit an inward movement of the cutters, thereby effecting their release in the hole.

130

21. In an underreamer, the combination of a body, a pair of expandible cutters mounted on the body, spring actuated means cooperating with the cutters and supported in the body, said body permitting a longitudinal movement of the cutters on the body, said body having inclined supporting faces receiving the inthrust of the cutters when the same are in their completely expanded position, and operating by an upward movement of said body when the cutters are stuck in the hole, to withdraw said supporting faces and permit an inward movement of the cutters, thereby effecting their release in the hole.
22. In an underreamer, the combination of a body, a pair of expandible cutters mounted to move longitudinally in the body, means for rigidly supporting the inthrust of the cutters when completely expanded, and means for effecting a slight contraction of the cutters rendered operative by an upward movement of the body when the cutters are stuck and held fixed by the wall of the hole.
23. In an underreamer, the combination of a body, a pair of cutters mounted on opposite sides of the body and capable of longitudinal movement on the body, said cutters having shanks at their upper ends, each of said shanks having a groove on its side with an elevated shoulder, a transverse key in the body cooperating with the shoulders to limit the downward movement of the cutters, spring actuated means cooperating with the cutters for pulling the same upwardly on the body, said cutters and said body having means cooperating to effect the expansion and collapsing of the cutters by a downward movement of the body and an upward movement of the body with respect to the cutters.
24. In an underreamer, the combination of a body, a pair of oppositely disposed cutters having shanks extending upwardly in the body, each of said shanks having a groove on its side face with an elevated shoulder, a transverse key in the body cooperating with the shoulders to limit the downward movement of the cutters, spring actuated means for pulling the cutters upwardly in the body, said body and said cutters having means cooperating to effect a slight inward movement of the cutters initiated by an upward movement of the body when the cutters are stuck and fixed in the hole, thereby effecting the release of the cutters.
25. In an underreamer, the combination of a body, a pair of expandible cutters supported thereby, the inner side of each cutter having a projection cooperating with the body in expanding and collapsing movement of the cutters, each cutter also having a recess on its inner side, the said recesses and projections being located so that when the cutters are collapsed the projection in one cutter is received in the recess of the other cutter.

Signed at Los Angeles, California, this 1st day of August, 1921.
